UNITED STATES PATENT OFFICE.

FRIEDRICH ZIEGENFUSS, OF ESSEN-ON-THE-RUHR, GERMANY, ASSIGNOR TO FRIED. KRUPP AKTIENGESELLSCHAFT, OF ESSEN-ON-THE-RUHR, GERMANY.

PROJECTILE.

932,229.

Specification of Letters Patent. Patented Aug. 24, 1909.

Application filed January 12, 1909. Serial No. 471,967.

To all whom it may concern:

Be it known that I, FRIEDRICH ZIEGENFUSS, a subject of the Emperor of Germany, and a resident of 119 Dreilindenstrasse, Essen-on-the-Ruhr, Germany, have invented certain new and useful Improvements in Projectiles, of which the following is a specification.

The present invention relates to a projectile having a fuse which is connected to the projectile-body by means of a bushing, and the object of the invention is to form the bushing and the fuse in such a manner that the hollow space of the projectile serving to receive the filling shot becomes as great as possible. In accordance with the present invention, this object is attained by providing the bushing with a trunnion extending toward the projectile point and by providing the fuse with a recess for receiving the trunnion.

In the accompanying drawings, Figure 1 is an axial longitudinal section of one embodiment of a projectile constructed according to the invention, and Fig. 2 shows a similar view of a projectile of the same type of the construction hitherto used.

Reference will first be had to the projectile shown in Fig. 1. The projectile is formed as a shrapnel and is provided with a burning fuse. The bushing A¹ is screwed into the projectile-body A, which contains the filling shot B. The bushing is provided with a central hollow trunnion a² which extends toward the projectile-point and is provided with exterior threads engaging in a threaded bore c⁴ in the burning fuse C. The hollow space of the trunnion a² contains the fulminating charge c² of the burning fuse. Through the medium of a bore a³ provided in the wall of the hollow trunnion a², the fulminating charge c² communicates with the fulminating channel c⁴ which is provided in the base c³ of the burning fuse. The projectile shown in Fig. 2 mainly differs from the projectile just described in having the base c³ of its burning fuse provided with an exteriorly threaded trunnion

c⁵, which extends toward the base of the projectile and which is screwed into a threaded bore in the bushing A¹ and contains the fulminating charge c² of the burning fuse.

In the projectile according to Fig. 2, the fuse projects farther into the hollow space of the projectile than does the fuse of the projectile according to Fig. 1, as the trunnion c⁵ in Fig. 2, which extends toward the base of the projectile, must be of comparatively great length in order to provide a reliable connection between the fuse and the bushing A¹. The projectile according to Fig. 1 can, therefore, hold a greater number of filling shot than the projectiles of the construction hitherto used, and it, therefore, also gives a better effect.

Having thus described the invention, what is claimed and desired to be secured by Letters Patent is:

1. A projectile having a projectile body, a fuse provided with a recess, and a bushing for securing the fuse to the body, said bushing having a trunnion extending toward the projectile point and engaging in the recess of the fuse.

2. A projectile having a projectile body, a fuse provided with a recess, and a bushing for securing the fuse to the body, said bushing having a trunnion extending toward the projectile point and engaging in the recess of the fuse, said trunnion being hollow and containing part of the fuse.

3. A projectile formed as a shrapnel and having a projectile-body, a burning fuse provided with a recess, and a bushing for securing the fuse to the body, said bushing having a hollow trunnion extending toward the projectile point and engaging in the recess of the fuse; said trunnion containing the fulminating charge of the burning fuse.

The foregoing specification signed at Barmen, Germany, this 4th day of December, 1908.

FRIEDRICH ZIEGENFUSS. [L. s.]

In presence of—

OTTO KÖNIG,
WALTER EZKIESKAMP.
